UNITED STATES PATENT OFFICE

MORRIS FALK, OF FITCHBURG, MASSACHUSETTS

KEY CUTTING MACHINE

Application filed December 5, 1927. Serial No. 237,603.

This invention relates to a machine for cutting keys.

The principal objects of the invention are to combine with a key-cutting machine such as shown in my prior applications, Serial Nos. 184,643, filed April 18, 1927 and 229,831, filed October 31, 1927, the first of which has become Patent No. 1,750,218 a key cutting device on the same shaft, and a reversible clamp 10 for use in cutting keys of different types; to provide a reversible clamp for holding the blanks of such a nature suitable for cutting two entirely different kinds of keys; and to provide the same with mechanism by which 15 the reversal of the clamp will be simple and expeditious, and with an improved form of gauge for locating a master key and blank. Other objects and advantages of the invention will appear hereinafter.

Reference is to be had to the accompanying drawings in which

Fig. 1 is a plan of a combined machine constructed in accordance with this invention;

Fig. 2 is an end view;

Fig. 3 is a sectional view on the line 3—3 of Fig. 1 showing the reversible clamp arrangement in end elevation, and

Fig. 4 is a plan of the latter, showing a blank and master key in position for cutting.

The machine involves a base 10 as usual on which are head stocks or bearings 11 with a spindle operated by a pulley 12, and having two rotary cutters 13 and 13^a thereon. The tail stock 14 is adapted to receive a center 15 on which is arranged a guide 16. This is used only when cutting a blank B from a key K. The guide 16 is designed to have the same relation to the key that the cutter does to the blank.

The machine is provided with a shaft 20 extending longitudinally thereof and having upon it a screw for adjusting longitudinally a frame 23 which is pivoted on the shaft 20 to swing from horizontal position, shown especially in Fig. 1, to an upright position as shown in Fig. 2.

On this frame is a carriage 24 preferably carrying two clamps 25, although in some cases one of these clamps can be omitted.

These clamps or jaws are screwed down by

thumb screws 26 to clamp the blank or the master key, if that is used, in the same relative positions on the two clamps.

On the front of this carriage 24 is a freely turning shaft 27 having two gauges 28 thereon. It is provided with a knurled end 29 or handle so that it can be turned up and down so that these gauges 28 can be brought up into contact with the key. This shaft is provided with a coiled spring 30 having one end fixed to the shaft and the other to the carriage. This automatically moves the gauges out of the way, when not being used. The blank and key are shifted in the jaws until they both come into the same relationship with the two gauges 28, that is, these gauges are set up against the same element on both. Then the clamps are tightened and these gauges turned down to the position shown in Fig. 2 where they are out of the way. As the cutter 13 is rotating constantly, this cutter will cut a notch in the blank exactly in the desired position.

I have already stated that a screw or rack is a part of the shaft 20. This screw is engaged by a nut which is mounted on the frame 23, and by turning it through the handle 42 the frame 23 and carriage 24 will move along the shaft 20 in accordance with the rotation of this screw, so as to bring it to the proper positions to space the notches the right distances apart.

In cases where the key is lost, the number can be obtained from the lock or otherwise, and used to control the cuts. For this purpose, two discs 34 and 35 are used. They are mounted on shafts. I have shown each disc as being provided with a series of perforations as 36 and 37 which are spaced in accordance with the code of the manufacturer of the key. These codes are used for spacing the notches of the keys and for the depths in cut. Each manufacturer has his own code and of course there is a separate one for the spacing and for the depths. The code of only one manufacturer is indicated on the discs. These two discs, it will be understood, are detachable and adjustable, but in the use of the device are stationary. To make them readily detachable and replaceable each one has

a radial slot 60 and 61. They are set so that the dial mark 0 on each disc registers with a fixed pointer 38 and 39 respectively. One of these pointers 38 is a clamp held down by a thumb screw 40 which will loosen the pointer to permit removal of and replacement of the disc by others when that is desired or to turn the discs. The other disc is held down by a clamp 62 and thumb screw 63. The clamps 62 and 38 are wider than the slots 60 and 61. The discs are both set at the so-called zero point where the mark is shown, and then these discs can be used from then on to arrange for cutting the keys of the manufacturer 15 whose code is indicated thereon by the series of perforations.

On the ends of the central shafts are fixed two arms 42 and 41 respectively. On the end of the arm 42 is a spring pin 43 having a head 20 44 for raising it out of one of the holes in the disc 34, so that this arm can be put in one hole after the other of a certain series. Each time it is changed it will move the carriage 24 along the screw to position the blank in a new 25 place with respect to the cutter 13. This, of course, is done when the carriage is drawn back. The arm 41 also has a spring pin 45 operated by a lever 46 extending out over the end of the arm 41. This works in the same way 30 on the disc 35 to move the carriage 24 toward and from the cutter through a cam 56 to which the arm 41 is fixed. The cam 56 cooperates with a rod 53 on the slide. Obviously this will move the slide 24 in and out as in the 35 other case. The rod 53 with a spring 58 is used to return the slide and keep the rod 53 always in contact with the cam. The cam is held on the shaft by a thumb nut 66. A pointer 67 is shown on the handle 46.

40 It will be seen therefore that the carriage can be drawn back from the cutter by the arm 41 and then moved along by the arm 42 and the pin 43 put back in another hole in the disc to positively locate the carriage in that 45 respect. Then the arm 41 can be moved along to the next hole desired and the pin 45 allowed to slip into it so that the depth of the cut will be positively controlled. These operations are performed ordinarily when the 50 structure comprising the frame 23 and the carriage 24 is swung back to horizontal position.

55 In the use of this machine the two blanks are inserted into the two jaws 25 and one of them clamped in position. Gauges 28 are then turned upwardly so as to engage either the blank or the key and the other one is moved along until that is also engaged in that 60 way and then clamped. The gauges are then turned down. The user does not have to look over the top of the carriage or in behind the center. Now this frame 23 is turned down so that a spring latch 17 comes down 65 into a notch in a rest 18. In this way the

frame 23 is positively positioned. The latch 17 is released by a finger hook 19.

On the carriage is a reversible block 71 adapted to be secured in position in a slot either end around by a screw 72. One side 70 73 of the block is cut away. When cutting keys that have wide blades and are cut deep the block has to be placed with the cut-away portion at the front toward the cutter.

In order to adapt the machine for use in accordance with the above description, and also for use for cutting keys from master keys, and provided with means whereby the same machine is adapted to cut keys of quite different characteristics, I have extended the 75 spindle and placed upon it another cutter 13^a. The base is also extended to provide for this additional capacity for the machine. The frame 83 on this side is pivoted on the shaft or rod 20 like the frame 23 on the right hand 85 side. It is provided with a carriage 74 on which is centrally swiveled a bar 89. On this bar are one or more clamps 75 adapted to be held down on the bar by thumb screws 76 for clamping a master key K and a blank 90 B to be cut.

To space the blank in the right position, the master key is clamped in one of the clamps and a slidable rod 79 having two gauges 78 on it, is moved to the desired point and turned up so that one of these gauges comes against a certain point on the master key. Now the blank is moved in its jaws until it comes to the same position with respect to the other gauge 78, and then the jaw is 100 clamped to hold it. The rod 79 is provided with a spring 80, one end of which is secured in the rod and the other on a stationary part of the frame, thus turning down the gauges to the position shown in Fig. 3, when the 105 handle 79 of the rod is released. This rod is made long so as to provide for operating on keys of widely different characters. The pivoted frame has a forward extension 81 which is adapted to rest on a planed projection 82 cast on the base 10 to hold it in horizontal position during the key cutting operation. 110

This so-called carriage 74 is slidably 115 mounted on the frame 83 to permit it to be moved for the different cuts. The bar 89 is swiveled thereon on a screw 84 having a thumb head 85 by which it is turned in opposition to a spring 86 to hold the clamps 120 down on the bar 89. The jaws 75 are quite different on the two sides, front and back, and have jaw surfaces on both sides to grip keys of different characters, as for example, different widths. 125

When it is desired to cut keys suitable for being held in the jaw shown at the rear in Fig. 3, the screw 84 is released and the whole clamp member 89 turned around 180 degrees. This is shown half-way around in dotted 130

lines in Fig. 4. This presents the other jaws to the front and an entirely different pair of keys are inserted in it and one of them cut in the manner previously described. This constitutes a simple and convenient way of providing for the cutting of several different kinds of keys in the same machine. In the adjustment no parts are taken off, but they are merely loosened. Therefore, there is nothing that may be lost or displaced in the process. Of course the gauge, being mounted on the carriage 74, will serve for both sets of jaws.

This constitutes a very simple and convenient machine suitable for a wide range of work, and is practically universal in this industry.

Although I have illustrated and described only one form of the invention I am aware of the fact that changes can be made therein by any person skilled in the art without departing from the scope of the invention as expressed in the claims. Therefore, I do not wish to be limited to the exact form shown, but what I do claim is:—

1. In a key cutting machine, the combination of a rod, a carriage pivotally mounted on the rod, a bar on the carriage, a pair of clamps on the bar, each clamp having front and rear jaws adapted to clamp different kinds of keys in position, a pivot between the jaws on the carriage about which the bar is adapted to be reversed to present either pair of jaws to the front, and means for clamping the jaws down in either position.

2. In a key cutting machine, the combination with a movable carriage and a cutter, of a bar swiveled on the carriage to swing around an axis normal to the surface of the carriage to reverse its front and rear edges, and jaws on the bar having different front and rear clamping surfaces whereby keys of different characters may be held in the jaws and presented to the cutter by reversing the bar.

In testimony whereof I have hereunto affixed my signature.

MORRIS FALK.
